UNITED STATES PATENT OFFICE.

LOUIS W. HASKELL AND ERWIN W. THOMPSON, OF NEW YORK, N. Y.

PRESS-BOX.

No. 815,291.

Specification of Letters Patent.

Patented March 13, 1906.

Application filed July 22, 1905. Serial No. 270,845.

To all whom it may concern:

Be it known that we, LOUIS W. HASKELL and ERWIN W. THOMPSON, citizens of the United States of America, and residents of the city, county, and State of New York, have invented certain new and useful Improvements in Press-Boxes, of which the following is a specification.

Our invention consists in a new and useful improvement in press-boxes for use with oil-presses employed for the purpose of expressing cotton-seed and similar vegetable oils.

The object of the invention is to enable the box to be cast from steel in one piece instead of being built up by the more expensive and less satisfactory process of riveting and bolting or otherwise fastening together an assemblage of various elements; and a further object is to enable the entire box to occupy a minimum amount of space and to provide a maximum opening between the boxes for receiving the cakes.

The invention consists, essentially, in the construction, arrangement, and combination of parts, substantially as will be hereinafter described and then more specifically pointed out in the clauses of claim.

In the accompanying drawings, Figure 1 is a view in elevation of a press composed of a plural arrangement of our improved press-boxes. Fig. 2 is a top plan view of one of the boxes. Fig. 3 is a side view of the same. Fig. 4 is a transverse view of four boxes, the upper one being shown in end elevation, the one below it in section on the line $x-x$ of Fig. 2, and the remaining two lower ones being shown in section on the line $x'-x'$ of Fig. 2. Fig. 5 is a detail perspective view of one corner of the box.

Similar numerals of reference designate corresponding parts throughout the different figures of the drawings.

Heretofore cast iron or steel boxes have been unsatisfactory, largely because in providing for a maximum cake-space the solid part as heretofore designed had to be reduced until the boxes became too fragile. On the other hand, "built-up" boxes, as we term them, being composed of a plurality of parts fastened together, have a tendency to come apart at the joints, especially the joints of side walls. When the box is made in a single piece from cast-steel or similar material, these disadvantages are obviated, especially when the box is patterned in the peculiar form of our present improvement, and hence

we gain many benefits and provide a box which is extremely useful and which does its work with remarkable facility.

1 designates the main part of the box, 60 which is a steel plate or block, preferably of square or rectangular form, and of such substantial thickness as is suited to give it strength and enable it to perform its work. It is provided with a grating 2, consisting of 65 parallel grooves formed in the upper face of part 1. In the old style of boxes this grating 2 is commonly removable. We prefer to cast it solid with the rest of the box, although it may be made as a removable part, if desired. 70 On the grating 2 rests the mat 3, which is perforated, and on mat 3 the cake rests.

The main part 1 is provided laterally on its two longer sides with the outreaching flanges or sections 4, reduced in thickness below the 75 thickness of the part 1, said reduced sections 4 being made integral with the main box 1 and being drilled at 9 for the bolts 11, which keep the boxes in position relatively to each other, said lateral sections being provided at 80 their middle points with notches 15, which loosely engage the upright rails 22 of the main frame of the press. (Indicated in Fig. 1.)

The reduced sections 4 are shaped below with the flanges 5, whose inner opposing faces 85 are vertical, as indicated in the showing of the top box in Fig. 4. At the extremities of the flanges 5 are the lips or guides 6. The larger portion of the material of the flanges 5 is cut away at 8, leaving only a short portion 90 at each end 6 the full size. (See Fig. 3.)

The distance between the inner faces of flanges 5 is slightly more than the width of the top grooved face of the main box 1, and between these faces the mat 3 of the lower 95 box is received and makes a fairly tight fit. The lower box with its mat reciprocates up and down in this space between flanges 5 for the purpose of compressing the cake between the mat 3 and the bottom of the box 1. 100

The flanges 5 are integral with the box 1. Furthermore, at the ends of the reduced lateral sections 4, alongside the vertical faces 16 on the sides of box 1 and above the guides 6, formed on flanges 5, are corner seats or surfaces 7, as indicated in Fig. 5, which are flat and smooth and are depressed below the surfaces of the sections 4, and in these depressions or recesses, above the surfaces 7, are received at times the guides 6 of the box above— 105 as, for instance, when two boxes like the two lower ones in Fig. 4 are telescoping with each

other with no cake between them to be pressed. The exact shape, however, and form of these corner-surfaces 7, of which, obviously, each box has four, may vary within wide limits and must correspond to the general shape and structure of the box.

It is important in an oil-press of this type that the mat should fit closely between the parts 5 5 of the box and should be retained there during its movements, never being allowed to drop below the bottom ends of the guides 6—that is to say, it should always be embraced by the depending flanges 5 at the sides of the box, for if it should be otherwise it might swing sidewise to a small amount when it drops down near the lower ends of the guides 6, which would cause it to slip underneath the guides 6, and this would cause damage when the box below carrying said mat was again lifted. The lips or guides 6, one at each corner of the box, hold the boxes telescoped when opened to their full width, as indicated in the showing of the top box and the one immediately below it in Fig. 4, and these lips or guides 6 allow a wider opening than would otherwise be possible.

We do not limit ourselves to making this box of cast metal. The same result in the matter of telescoping may be attained in a built-up box by planing or milling away the end portions of the reduced sections 4 to provide the depressed corners 7, which will receive the guides 6 in such a way that said guides will not strike the surfaces 7 when the boxes are closed together in the manner shown in Fig. 4, the two lower boxes without any cake between.

As our invention relates to a press-box forming one member of a series of boxes employed in an oil-press of the multiple-box type, we have indicated in Fig. 1 the general form of such a press consisting of the corner-columns 21 and the head-tree 20, connecting the columns 21. Within the columns is a series of boxes 1, as many in number as is

desired, which are operated by hydraulic or other pressure to compress the cake between them and express the oil.

Having thus described our invention, what we claim as new, and desire to secure by Letters Patent, is—

1. In a press-box for an oil-press of the multiple-box type, a main part having longitudinal lateral sections of less thickness, said sections having downwardly-projecting guides near the ends, and having also on their upper surfaces thinned-out portions near the ends, so that two boxes may telescope and the guides on the one enter the recesses above the thinned-out portions on the other. 60

2. In a press-box for oil-presses of the multiple type, a main portion having a grating and designed to carry the mat and having its longitudinal sides practically parallel, said sides having lateral sections of reduced thickness, which sections have corner depressions above and corner-guides below, all arranged to permit the telescoping of two contiguous boxes and the entry of the guides on the one into the depressions on the other. 70

3. In a one-piece press-box for multiple presses, a main portion having a grating and parallel sides, said sides having integral sections of reduced thickness, and provided with flanges below, which afford inner opposing vertical faces, having a somewhat smaller distance from each other than the parallel sides of the main portion, said box having corner depressions above and projecting guides below, whereby two adjacent boxes 80 are always kept in telescope with each other to prevent displacement of the mat, substantially as described. 75

Signed at New York City this 19th day of July, 1905.

LOUIS W. HASKELL.
ERWIN W. THOMPSON.
